UNITED STATES PATENT OFFICE.

MARTIN L. MUNSON, OF NEW YORK, N. Y.

FOLDING PHONOGRAPHIC HORN.

No. 813,814.

Specification of Letters Patent.

Patented Feb. 27, 1906.

Application filed July 18, 1905. Serial No. 269,426.

To all whom it may concern:

Be it known that I, MARTIN L. MUNSON, a citizen of the United States, and a resident of the city of New York, borough of Manhattan, 5 in the county and State of New York, have invented a new and Improved Folding Phonograph-Horn, of which the following is a full, clear, and exact description.

This invention relates to horns such as are 10 attached to phonographs or similar instruments for intensifying sound and throwing it in a desired direction.

The object of the invention is to produce a horn of simple construction which may be 15 folded so as to occupy a small space, enabling the horn to be conveniently carried or packed for transportation.

The invention consists in the construction and combination of parts to be more fully 20 described hereinafter, and definitely set forth in the claims.

Reference is to be had to the accompanying drawings, forming a part of this specification, in which similar characters of reference 25 indicate corresponding parts in all the figures.

Figure 1 is a perspective view of the horn, representing the same in its opened or expanded condition. Fig. 2 is a longitudinal vertical section of the horn when expanded 30 as in Fig. 1, and Fig. 3 is a side elevation showing the horn in a folded or collapsed condition.

Referring more particularly to the parts, 1 represents the body of the horn, which is 35 preferably composed of leather, cloth, metal, paper, or similar collapsible material. This body has the same general form as usually found in horns of this kind, comprising a contracted neck 2, which attaches to a nipple or 40 mouthpiece 3. As indicated, the mouthpiece 3 is preferably of conical form and should be constructed of metal or similar material. At the inner or large extremity of the mouthpiece a plurality of ribs or stays 45 4 are attached rigidly, and these stays preferably consist of flat strips or bars of metal, the flat sides whereof are attached longitudinally to the body 1 of the horn. Near 50 their outer extremities these stays 4 are connected by a plurality of links 5, arranged between the stays and pivotally attached thereto at the points 6, as will be readily understood. These links 5 are formed with centrally-disposed joints 7, which joints "break" 55 inwardly or in the direction of the mouthpiece. At the joints 7 pull-rods 8 attach,

and these extend toward the mouthpiece 3 and are attached to a movable ring or collar 9. This collar 9 has preferably the form of a frustum of a cone.

When the links 5 are all straightened out or extended, as indicated in Fig. 1, they operate to maintain the metal frame of the device in its most expanded condition. The construction of the joints 7 is such that when 60 the horn-frame is opened out, as indicated, the horn will maintain itself in this open condition. When it is desired to fold the horn, the ring or collar 9 will be grasped and forced in the direction of the extremity of the 70 mouthpiece. In this way the pull-rods 8 operate upon the links 5 so as to break the joints 7. In this way the outer extremities of the stays or ribs 4 are brought together, and when completely folded the body 1 of the 75 horn will collapse so that the horn will present substantially the appearance shown in Fig. 3. When in this condition, the horn may be very conveniently carried about or packed for shipment and may be readily 80 opened out for immediate use when desired.

It should be observed that the metal parts of the horn when attached together constitute a light framework or frame giving the open horn the required form. It should be 85 understood that when opened out the connected links 5 constitute a jointed ring completely encircling the body of the horn.

Having thus described my invention, I claim as new and desire to secure by Letters 90 Patent—

1. A horn of the class described, having a collapsible body, a plurality of stays attached to said body and extending longitudinally thereof, and jointed links connecting 95 said stays and adapted to maintain the same apart.

2. A horn of the class described, having a collapsible body and a mouthpiece attached thereto, a metallic frame attached to said mouthpiece and to said body, said frame comprising jointed links, a collar slidably mounted on said mouthpiece, and rods connecting said links with said collar for actuating said frame.

3. A horn of the class described, having a mouthpiece and a collapsible body, an extensible ring adapted to open said body and means for actuating said ring from a point near said mouthpiece.

4. A horn of the class described, having a mouthpiece and an expandable body, a plu-

rality of links jointed together and pivotally supported on said body to expand the same.

5. A horn of the class described, having a collapsible body, jointed links attached to said body and forming an extensible ring, a mouthpiece attached to said body, a sliding collar on said mouthpiece and pull-rods connecting said collar with said links.

in testimony whereof I have signed my name to this specification in the presence of two subscribing witnesses.

MARTIN L. MUNSON.
